UNITED STATES PATENT OFFICE.

WILLIAM ERASTUS WILLIAMS, OF CHICAGO, ILLINOIS.

HIGHWAY ROAD.

1,423,893.

Specification of Letters Patent. Patented July 25, 1922.

Application filed August 11, 1920. Serial No. 402,864.

To all whom it may concern:

Be it known that I, WILLIAM ERASTUS WILLIAMS, a citizen of the United States, a resident of Chicago, in the county of Cook and State of Illinois, have invented a new and useful Improvement in Highway Roads, of which the following is a specification.

My invention relates to highway roads that are intended to be used for automotive vehicles such as automobiles of all types including heavy trucks and to be used with horse drawn vehicles as well.

The object of my invention is to produce a roadway that would be as nearly permanent in character as possible, require the least amount of repairs, stand the heaviest traffic with the least injury and at the same time produce a road that may be cheaply made and installed in service. The basic feature 20 of my invention is involved in the peculiar construction and arrangement of a metal track and the means of installing it and holding it in place in the roadway.

Reference will be had to the accompanying drawings in which Figure 1 is a transverse section of what might be termed a double track highway road or a road provided wide enough for two of the largest vehicles to pass each other on the tracks of the 30 highway.

Figure 2 is a plan view of what is shown in Figure 1.

Figure 3 is a plan view of a single section of my track.

Figure 4 shows a means of joining the sections of the metal track.

Figure 5 is a plan view of a sheet of metal of which the metal track of the road is made.

Figure 6 is an end view of the part shown 40 in Figure 5.

Figure 7 is an end view of the plate after it is bent to form from the sheet shown in Figure 5 and Figure 6.

Figure 8 is a side elevation of the metal track alone.

Figure 9 is a plan view of a modified form of the track.

Figure 10 is a sectional elevation of the piece of track shown in Figure 9.

Figure 11 is another modified form of the track.

Figure 12 is a sectional elevation of the track shown in Figure 11. Figure 13 is a washer used with the tie rods.

It has been well demonstrated that the 55 cement concrete roadway is more lasting and gives better service than almost any other roadway that has yet been devised for all classes of highway vehicles, including automobiles, but it has the defect of being 60 nearly inelastic, and this feature under certain conditions leads to loosening the concrete from such reinforcement as may be used and to subsequent disintegration. These conditions often exist when the soil 65 beneath the roadway is such that moisture changes its roadway supporting capacity at different points and allows it to bend under the strains of heavy vehicles.

In the construction herein set forth I employ 70 steel rails capable of carrying any probable load without such bending as might cause cracking of a concrete structure associated therewith.

Further, the sections of the rail are made 75 sufficiently narrow and short to allow each slab to act as an independent member in the roadway to accommodate itself to frost, temperature and moisture variations in the subsoil in the body of the road itself. 80

In the drawing 1 indicates a flat sheet of metal of suitable thickness, depending upon permissible cost and the heaviest loads that are likely to be carried on the road. It is assumed that $\frac{1}{4}$ to $\frac{5}{16}$ inch plate is sufficiently 85 thick for the purposes of the road as here shown, although thicker plates may be used.

This plate has its edges expanded in a well known manner of making expanded metal, leaving the open spaces 2 as indicated in 90 Figures 5 and 6. The purpose of expanding the edges of the sheet is two fold. One is to give depth of girder to the side walls of the sheet after it is bent in channel form as

is indicated by Figure 7 and further to furnish apertures in the side walls of the channel for the admission therethrough of the cross bonding rods or reinforcing rods for the concrete. The two edges of the sheet 95

1 are indicated by 3 and are left rather wide 100 and stocky to furnish a body of metal for the edges of the flanges of the channel shape when the sheet has been bent into channel form.

The sheet 1 is bent into the channel form 105 4 having the side flanges 5 as indicated by Figures 7 and 8 and when this channel is incorporated into the track blocks or sec-

tions there extend through the apertures 2 the transverse reinforcing rods 6. These rods are shown in plan in Figure 2 and in elevation in the roadway in Figure 1. The 5 steel channel 4 is embedded in a concrete block 8 tied by the transverse rods 6 and by longitudinal rods 7 extending across the ends of the transverse rods on each side of the main rail channel 4 and thus each section 10 of the steel track is bound into a concrete block 8 substantially the same length as the steel channel rail piece. The length of these blocks depends upon the nature somewhat of what forms the earth base of the 15 roadway.

Where extreme variations in temperature and moisture and bulging conditions are encountered these lengths will be rather short, perhaps not to exceed 10 to 12 feet, or in 20 that neighborhood, but where there is a fairly good subsoil these lengths may be exceeded. The point is to make each individual block so short that any unequal bulging or support given by the soil in varying 25 weather conditions may be taken up by a sort of a hinged action between the several blocks of the roadway.

Further the channel rails, together with their associate concrete are intended to be 30 stiff enough to transmit over the entire base, the load to be carried by any set of wheels so that even though there might not be a good bonding of each block in the roadway, the traffic would automatically force a 35 good seating of each rail into the soil base of the road.

The several blocks are joined together in the roadway by having the ends of the channel rails 4 made to telescope each other for 40 a short distance as is indicated in Figures 3 and 4. One end of each channel is made smaller as shown at 10 and offset slightly at the top intended to make an overlap of the pieces as they are joined together in the 45 road. The concrete slabs attached to a part of the channel rail are divided by short strips of iron embedded in the end of each block with a filling of elastic material such as asphalt as is indicated by the joint 9 in 50 Figure 2. The channel rails 4, together with their blocks of concrete 8 are arranged to correspond with the gage of standard vehicles, and the channels are wide enough to receive automobile tires and provide in 55 addition narrow marginal spaces. The two rails 4 forming the single track are bound together by cross rods 11 for the purpose of holding the two rails to gage. These rods are inserted through holes provided in the 60 molding of the concrete into the channel rails 4.

In making the several rail blocks 8 of concrete I fill in the spaces with macadam, broken stone or gravel 12 and on the outside 65 margins of the rail I also provide a margin

of macadam, broken stone or gravel as indicated by 13. In place of macadam, broken stone or gravel these blocks may be blocks of concrete or other suitable road material, when desired.

One of the first essentials of a good roadway is drainage and while it has been the custom to provide tile or subsoil drains for high class roads, trouble has been encountered by the moisture disturbing the supporting base of the road even though tile drains were present. The concrete or other roads of similar types begin to show their failings usually on the margin of the roadway and breaks that take place there seem 70 to, as it were, ravel off the edges and gradually extend over into the central portions of the roadway until the road is seriously damaged or destroyed. This may sometimes be accounted for by the fact that 75 through the central body of the roadway no moisture reaches the earth beneath and hence this ground remains somewhat firm and undisturbed by variations and moisture conditions. The water that falls on the top 80 of the road is substantially entirely drained off to the edges of the roadway, which causes the edges of the roadway to receive an undue amount of moisture measured by any given rain fall. In other words it may be 85 said that the immediate edge of the roadway receives from three to four times the normal average rain fall for any given area as it must take the water from the whole surface of the road. This has the effect of 90 causing the edges of the roadway to take the rain fall of what would amount to two or three times the normal rain fall of the region and produces an excessive softening 95 of the soil at the edges of the road surface 100 and this is where the road supporting material is put to its severest strains and burden and therefore the breaking of the roadway is invited as it were at the edges, caused 105 by the discharge of the excessive moisture 110 from the central portion of the roadway on to the edges.

The arrangement of my macadam sections or broken stone or gravel sections 12 and 13 as shown permits the water that gathers on 115 any single slab to be discharged down through this material and in the earth face of the roadway I provide longitudinal tile drains 14 underneath this porous material and at suitable intervals I arrange cross 120 escape tile drains 15 which insures a drainage of the face of the road.

Any softening of the base which takes place anyway in a varying degree, due to 125 climate changes will take place in a balanced relationship to any given slab or given section of my roadway and thus that particular section may accommodate itself to the base with perhaps slight distortion of the general base surface, but not a suffi- 130

cient amount to damage the surface of the roadway. The concrete reinforcing, together with the channel rail is intended to so bind the single units or blocks 8 that they 5 will be sufficiently stiff to embed themselves into a uniform bearing on to the roadway underneath whenever there occurs an inequality in the subsoil due to excessive moisture that permits a bulging movement of 10 the soil itself.

In the construction of this roadway the several slabs 8 with their reinforcing bonding and channel rail 4 may be made up at a central plant as individual slabs and cured 15 in the plant to a proper degree of set of the concrete in a yard and then when the concrete has properly set and aged and tempered under the best conditions possible these blocks may be carried out by a motor 20 truck provided with suitable derrick constructions and deposited in the roadway slab by slab in their entirety and thus permit the road to be built at a much less cost than is possible where the concrete is laid 25 directly in place in the roadway itself.

A rod is often damaged by use before the concrete is fully set, and this feature is taken care of by the method of manufacture of my road as just described.

30 In certain sections of a roadway where hills are encountered a smooth metallic surface such as my channel section provides may not give sufficient traction to overcome the grades on hilly portions of the roadway.

35 To provide for this I arrange a slightly corrugated surface for the top surface of the channel sections 4 as is indicated in Figures 11 and 12 wherein 16 indicates the corrugations pressed into the top surface of the road

40 rail 4. In place of the corrugations as shown I may when desired expand the metal of the top surface of the rail 4 or the web of the channel 4 in the same manner that I expand the sides of the plate as shown in

45 Figure 5 and when this is done it will have open spaces 17, Figs. 9, 10. These spaces will be filled with the concrete material and thus the metal on those surfaces will appear only in spots and the concrete will extend

50 up and make a frictional contact surface for the tread of the wheel. The concrete may wear down slightly below the metal of the steel and thus the edges of the steel itself will give an adhesive effect to the tread of

55 the wheel. Further the apertures extending through the surface of the plate and channel rail will aid in the bonding of the concrete within the body of the channel.

It may appear that a smooth surface that 60 is now given a concrete road occasions but slight wear on the tires of the vehicles yet the tire wear will be less on the smooth surface of my rails than perhaps on any other material, even that of a relatively soft asphalt surface. The metal surface of the rail

will be quite smooth and even and there will be little or no abrading material upon it, whereas with a cement concrete surface there is a rough surface that abrades the tire as the latter is constantly changing in degree 70 of compression and is continually slipping slightly when the vehicle is in use. The same thing occurs, to some extent, on common asphalt roads the asphalt holding gritty materials. Slip of the tire also occurs when 75 steel is used but the steel surface the slip of this rubber in contact with the steel will wear the rubber less than perhaps any other material available for road service in all places excepting on the incline where adhesion is required and produced by means equivalent to what I have shown in my Figures 9, 10, 11 and 12.

What I claim is:—

1. In a structure of the class described, a 85 channel rail laid longitudinally with the roadway, with the web of the channel furnishing the tread surface of the rail and having its flanges expanded for the purpose of giving depth, saving metal and for apertures for the entry of concrete; in combination with a concrete mass in which the channel is embedded on all sides excepting the top surface of the web and a series of reinforcing rods extending through the web of 90 the channel transversely binding the concrete on either side of the channel.

2. In a structure of the class described, a vehicle track composed of metallic channel sections having the flanges downward and 100 the web of the channel upward for the wearing surface and embedded in concrete and bound thereto by metallic reinforcements running transversely of the channel and the margins of the said concrete bound also 105 longitudinally in parallel relation with the channel rail by metallic reinforcements.

3. In a structure of the class described, a metallic road rail made of a flat sheet having the metal of the edges of the sheet expanded furnishing apertures in the plate and formed with the expanded sides into the flanges of the channel and with the web of the channel furnishing the road surface and bonded into a road material aggregate on 110 each side of the said channel.

4. In a structure of the class described, the combination with a rail consisting of a flat metal plate having its lateral marginal portions bent downward and provided with 115 apertures, of a concrete base enveloping said marginal portions and engaging in said apertures and upwardly flush with the rail.

5. In a structure of the class described, a plurality of rail sections, channel shaped, 125 with the webs of the channels forming the wearing road surface and with the flanges embedded in a suitable road material, apertures in the flanges of the said channel and with the road material bonded through these 130

apertures and with tie rods connecting the channel sections together to hold them to gage.

6. A road unit consisting of a metal plate 5 adapted in width to receive any ordinary wheel and bonded in the middle portion of a materially wider concrete slab of approximately the same length, the whole constituting a pre-formed unit to rest upon a suitable 10 road base and with other like units form continuous parallel lines of wheel supports of a roadway.

7. In a structure of the class described, a series of metallic rails extending longitudinally 15 and furnishing a part of the tread bearing surface of the road and each rail bonded in a concrete slab and the several slabs having rails interlocked at their ends forming a continuous tread for the rail part 20 of the road.

8. In a structure of the class described, a metallic rail forming a part of the wearing surface of the road and having flanges extending in vertical relation to the road surface 25 face and said flanges perforated by having the body of the flanges expanded in the form of expanded metal and bonded into the road aggregate.

9. The combination with blocks, approximately 30 impervious to water, arranged in continuous parallel lines separated by a space materially less than the usual distance between vehicle wheels and projecting laterally far beyond the usual paths of 35 wheels spanning, or on opposite sides of said

space, of material in said space adapted to allow water to pass to the stratum beneath; whereby water escapes from all parts of the roadway while barred from parts immediately below the load bearing area. 40

10. The combination with continuous lines of parallel, impervious broad slabs arranged to receive on their middle portions and at a material distance from their margins the wheels of ordinary vehicles, of porous material 45 at the lateral margins of the slabs, allowing water to escape to the strata below but only at a distance from points below the paths usually followed by vehicle wheels.

11. The combination with parallel lines of 50 impervious slabs each many times wider than the tire of any ordinary vehicle, of corresponding lines of metal plates fixed in the middle portion of each line of slabs to receive vehicle wheels, porous material between the 55 lines of slabs, and drainage conduits arranged to receive downwardly escaping water before it can reach portions of the roadbed immediately beneath the load-bearing slabs, whereby parts of the bed directly bearing 60 the load are kept comparatively dry at all times.

Signed at Chicago, in the county of Cook and State of Illinois, this third day of August, 1920.

WILLIAM ERASTUS WILLIAMS.
